UNITED STATES PATENT OFFICE.

ALFRED BLUMENTHAL, OF NEW YORK, N. Y.

OILING DEVICE.

1,370,273.

Specification of Letters Patent. Patented Mar. 1, 1921.

Application filed August 18, 1920. Serial No. 404,367.

To all whom it may concern:

Be it known that I, ALFRED BLUMENTHAL, a citizen of the United States, and a resident of the city of New York, borough of the Bronx, in the county of Bronx and State of New York, have invented a new and Improved Oiling Device, of which the following is a full, clear, and exact description.

The invention relates to fountain brushes of the type shown and described in the Letters Patent of the United States for a wall cleaning and sizing apparatus, No. 1,255,695, granted to me on February 5, 1918.

The object of the invention is to provide a new and improved oiling device arranged for thoroughly rubbing oil or similar liquid on wooden floors, walls, interior and exterior woodwork, furniture and the like.

Another object is to enable the user to readily manipulate the oiling device without danger of soiling the hands or clothes.

Another object is to prevent scratching or other injury of the surface treated with oil or similar liquid and to permit of conveniently oiling a large surface with a single charge of oil and without requiring much physical exertion on the part of the operator.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a perspective view of the improved oiling device;

Fig. 2 is a similar view of the applying member;

Fig. 3 is a similar view of the core of the applying member;

Fig. 4 is an enlarged sectional side elevation of the improved oiling device on the line 4-4 of Fig. 1;

Fig. 5 is a similar view of a modified form of the applying member in position on the reservoir containing the oil or similar liquid.

The reservoir 10 is adapted to contain oil or a similar liquid 11 and from the back of the reservoir projects a socket 12 which can be used as a handle to manipulate the device, but, if desired, a stick 13 may be attached to the socket 12 for conveniently using the apparatus on surfaces out of convenient reach

of the operator. The reservoir 10 is provided with a filling spout 14 for conveniently filling the reservoir with oil, and the said spout 14 is normally closed by a cap 15.

The under side of the reservoir 10 is provided with a depending socket 20 extending the entire length of the reservoir 10, and into this socket 20 is removably fitted an applying member 21 for applying the liquid 11 to a surface, as hereinafter more fully explained.

The applying member 21 consists of a core 22 and a covering 23, and the said core is made of sheet metal or other rigid material in the form of an elongated rectangular frame provided with a corrugated insert 24 extending from the open top to the open bottom of the core to provide a large number of passages or openings for the oil.

The covering 23 is preferably made of felt or similar fabric material, and completely incloses the core 22. The covering 23 fits snugly against the inner surfaces of the walls of the socket 20 thus closing the socket with the top of the covering 23, however, extending into the reservoir 10 to allow the oil to saturate and pass through the top of the covering and through the openings in the core 22 to the bottom of the covering 23.

The bottom of the covering 23 is provided with an applying element 25 which may be in the form of a number of overlying flaps of felt (see Figs. 1, 2 and 4) or a single strip of thick felt as illustrated in Fig. 5. In either case the applying element 25 is capable of flexing and as it practically forms a continuation of the covering 23 the oil saturates the applying element. The flaps forming the applying element are preferably fastened together by a row of stitches 30,

and stitches 31 may be used for fastening the thick strip of felt to the bottom of the covering 23, as shown in Fig. 5. It is understood that in either case the oil passing into the passages of the core 22 seeps through the bottom of the covering 23 and passes into the applying element 25 to be rubbed onto the surface to be oiled on the operator drawing the applying element over said surface. The core 22 is provided with

stops 35 preferably attached to one side and extending through the corresponding side of the covering 23 to abut against the edge of the corresponding wall of the socket 20 thus limiting the inward movement of the applying member 21 when pushing the same into place in the socket 20.

It is understood that in using the device, the operator draws the applying element 25 over the surface to be oiled and the operator by exerting pressure on the apparatus causes the applying element 25 to effectively rub the oil into the pores of the surface.

It is also understood that the lower portion of the applying member 21 projects below the bottom of the socket 20 and the applying element 25 projects from the bottom of the covering 23 to insure free flexing forward and backward of the applying element 25, when moving the device forward and backward with the applying element 25 in contact with the surface to be oiled. In case the applying element 25 becomes worn out it can be readily removed from the socket 20 and replaced by a new one.

It will be noticed that the front of the reservoir 10 as well as the ends are flat to permit the applying or rubbing element 25 to reach the edges of the surface to be oiled especially on adjacent walls or other joints and without danger of scratching or otherwise injuring the adjacent wall.

Having thus described my invention, I claim as new and desire to secure by Letters Patent:—

1. An oiling device, comprising a handled reservoir adapted to contain a liquid and provided with an opening extending the en-

tire length of the reservoir, and an applying member fitting into the said opening and comprising a hollow core of rigid material and a fabric covering inclosing the core, the inner portion of the covering being in contact and saturated with the liquid in the reservoir, the said core having a corrugated insert thereby forming vertical passages for the liquid and the said covering having a flexible projecting applying element.

2. An oiling device, comprising a handled reservoir adapted to contain a liquid and provided with an opening extending the entire length of the reservoir, an applying member fitting into the said opening and comprising a core of rigid material and a fabric covering inclosing the core, the latter having a corrugated insert forming passages, the said covering having a flexible applying element projecting from the bottom thereof.

3. In an oiling device of the type described, an applying member comprising an elongated rectangular frame forming a core, a corrugated insert fitting into the said frame and providing vertical passages for the liquid, and a fabric covering inclosing the said frame and provided at the bottom with a flexible applying element.

ALFRED BLUMENTHAL.
